UNITED STATES PATENT OFFICE.

CARL H. HITTENBERGER, OF SAN FRANCISCO, CALIFORNIA.

ABDOMINAL SUPPORT.

Application filed January 16, 1926. Serial No. 81,698.

My invention relates to improvements in abdominal supporters and the like wherein a pad is pressed inwardly and upwardly against the abdomen to exert an uplifting pressure thereon by means of spring members arranged to fit around the body of the wearer to apply the required pressure and to hold the pad in position.

The primary object of my invention is to provide an improved abdominal support.

Another object is to provide an improved support of the character described which will facilitate the placing and removing of the pad.

A further object is to provide an improved device adapted to obtain an increased rigidity of structure and to apply a firm and uniform pressure.

Another object is to provide a device which may be applied or removed without distorting the supporting members and without subjecting any portion of said members or the pad to excessive strain, thereby obtaining increased durability and insuring an accurate fitting throughout the life of the device.

A still further object is to provide an improved construction which may be economically manufactured and which will increase the comfort and effectiveness of the device.

I accomplish these and other objects by means of the improved device disclosed in the drawings forming a part of the present specification wherein like characters of reference are used to designate similar parts throughout said specification and drawings and in which,

Fig. 1 is a front elevation of my improved abdominal support.

Fig. 2 is a plan view of the device as shown in Fig. 1 and showing the manner in which the spring supporting members are swung outwardly when the pad is to be applied or removed.

Fig. 3 is an enlarged sectional detail of the pivot mounting by which each spring is secured upon the pad.

Referring to the drawings the numeral 1 is used to designate in general a pad of the character used in the mechanical treatment of enteroptosis, visceroptosis, intestinal stasis, floating kidney, and the like, the pad being shaped to meet the requirement of any particular individual and the treatment prescribed. The pad consists of a rigid plate 2, the inner side of which is covered by a suit-

able thickness of padding, the plate and padding being covered by a suitable covering 3 of leather or other suitable material.

The pad 1 is pressed inwardly and upwardly against the abdomen of a wearer by means of a pair of spring members 4 each having one end pivotally connected upon the front of the pad 1 and arranged to extend around the hips of the wearer to support and retain the pad in correct position. The ends of the spring members are pivotally mounted upon pivot pins 6 secured substantially parallel to the front of the pad 1 between forwardly extending flanges 7 of a channel member 8 secured upon the front of said pad, the ends of the spring members being preferably doubled back and riveted or otherwise secured to form bearing portions 9. The pins 6 are positioned near the center of the channel member 8 and the ends of the channel member extended a considerable distance beyond the pins to engage the edges of the spring members 4 for a purpose herein-after more fully explained.

The spring members 4 are provided with a suitable covering of leather or other suitable material and are shaped to fit around the hips of the wearer, said members being upwardly offset and shaped in a manner adapted to exert an upwardly lifting pressure against the pad 1. The free ends of the spring members are secured in back of the wearer preferably by means of a buckle 11 secured to one of the springs and arranged to receive a strap 12 secured to the other spring member. When the spring members are secured around the hips of the wearer the spring fits closely to the body and exerts a spring pressure against the pad without binding the hips and without causing discomfort to the wearer.

In operation the pad is fitted to the form and requirements of any particular patient. In applying the pad, the spring members 4 are swung outwardly upon their pivot mountings upon the pins 6 to a position such as indicated in dotted lines in Fig. 2 of the drawings. The pad is now placed in the desired position relative to the abdomen of the patient and the spring members swung rearwardly around the hips, said members automatically moving into correct position without requiring any material spreading or distorting of the springs. As the spring members 4 are moved to normal position extending around the hips of the wearer, the ends

of the members adjacent the pivot mountings move between the outwardly extending flanges 7 of the channel member 8, said flanges operating to rigidly brace the springs and to prevent any vertical movement of the spring ends relative to the pad. This is an important feature of my present invention as in this manner an extremely rigid structure is obtained thereby insuring the uniform and continued application of the desired pressure against the pad. At the same time, the pivotal mounting whereby the spring members may be swung outwardly permits the device to be easily and quickly applied without imposing any undue strain upon the ends of the members 4 and their mountings and without causing the spring members to be distorted. This feature is also of particular importance as it permits a more accurate fitting and increases the durability of the device.

While I have illustrated and described the preferred construction of my invention, the device is of course subject to modification in the specific details of construction and I desire to avail myself of all such modifications which may fall within the scope of the appended claims.

Having thus described my invention what I claim as new and desire to secure by Letters Patent is,

1. An abdominal support comprising a pad; a pair of springs pivotally mounted upon axis parallel to the front of the pad and adapted to extend around the hips of a wearer to hold the pad in supporting relation to the abdomen, said springs being arranged to be swung outwardly from the front of the pad whereby the support may be applied or removed without distorting the springs or pad; and means for preventing vertical strain upon the pivot mountings of the springs and to hold the ends of the spring in rigid engagement with the pad.

2. An abdominal support comprising a pad; a channel member secured in outwardly facing position upon the front of the pad; and a pair of springs pivotally mounted between the flanges of the channel mem-

ber and adapted to extend around the hips of a wearer to hold the pad in supporting relation to the abdomen.

3. An abdominal support comprising a pad; a channel member secured in outwardly facing position upon the front of the pad; and a pair of members pivotally mounted between the flanges of the channel member and adapted to extend around the hips of a wearer to hold the pad in supporting relation to the abdomen; and means for securing the free ends of the spring in back of the wearer.

4. An abdominal support comprising a pad; a channel member secured in outwardly facing position upon the front of the pad; a pair of pivot pins mounted between the flanges of the channel member adjacent the center thereof and substantially parallel to the front of the pad; and a pair of springs mounted upon the pivot pins and adapted to extend around the hips of a wearer to hold the pad in supporting relation to the abdomen, the portions of said springs adjacent the channel member being received between the flanges thereof to brace the ends of the springs and prevent vertical movement of the springs relative to the pad.

5. An abdominal support comprising a pad; a channel member secured in outwardly facing position upon the front of the pad; a pair of pivot pins mounted between the flanges of the channel member adjacent the center thereof and substantially parallel to the front of the pad; and a pair of members mounted upon the pivot pins and adapted to extend around the hips of a wearer to hold the pad in supporting relation to the abdomen, the portions of said springs adjacent the channel member being received between the flanges thereof to brace the ends of the springs and prevent vertical movement of the springs relative to the pad; and means for securing the free ends of the springs in back of the wearer.

In witness whereof I hereunto set my signature.

CARL H. HITTENBERGER.
